Attorney.

UNITED STATES PATENT OFFICE.

JOHN JAMES DIXON, OF BARRACKVILLE, WEST VIRGINIA.

SCRAPER AND TAMPING ROD.

Application filed July 11, 1923. Serial No. 650,928.

To all whom it may concern:

Be it known that I, JOHN J. DIXON, a citizen of the United States, residing at Barrackville, in the county of Marion and State of West Virginia, have invented certain new and useful Improvements in Scraper and Tamping Rods, of which the following is a specification.

This invention relates to tools for use 10 in connection with the operation of drilling and preparation for blasting in mines, quarries, etc.

It is common practice during the operation of drilling a hole for a blasting charge 15 or other explosive material to frequently scrape out and remove the small particles that have become detached by drilling, and, after a hole of the desired depth has been drilled and all of the particles removed, 20 an explosive charge is inserted in the hole and tamping material is packed thereon by means of a tamping rod.

It is the principal object of this invention to provide a combined scraper and 25 tamping rod which is well adapted to perform the two above mentioned operations, which is of sufficient length to accommodate deep holes, yet of novel construction so as to render it light and durable; and, which 30 is so constructed that the parts may easily be removed therefrom should they become worn or broken or should it be desired to substitute different sized parts, and to replace the required parts.

A still further object is to provide a 35 scraper and tamping rod which is constructed entirely of such materials that, should inflammable gas, coal dust, or other ignitable elements be encountered during the 40 operation of drilling or when packing tamping material in the hole, it will not be possible to cause a spark should any portion of the rod come in contact with a flinty substance, thus obviating the possibility of 45 causing a premature or inopportune explosion.

Other objects and advantages will appear in the following detailed description, taken in connection with the accompanying 50 drawings, forming a part of this specification and in which drawings:

Figure 1 is a plan view of a device constructed according to my invention.

Figure 2 is an enlarged view partly in 55 plan and partly in longitudinal section with a portion thereof being broken away.

Figure 3 is an end elevation of the device, and,

Figure 4 is a section taken on the line 4-4 of Figure 2. 60

In the drawings, wherein for the purpose of illustration is shown the preferred embodiment of the invention, and wherein similar reference characters designate corresponding parts throughout the several 65 views, the letter A indicates a scraper and tamping rod comprising a stem B; an extension C at one end of the stem B; a scraper D carried by the extension C, a head E formed on the stem B opposite the 70 extension C, and a cap F carried by the head E.

The stem B may be of a sufficient length for convenient handling and preferably is made of some light material, such as hard 75 wood, which in addition to rendering it flexible, makes easy the attachment of the several parts which will be hereinafter described. The one end portion of the stem B is reduced in size, providing a shank 8 80 and defining a shoulder 9. If desired, the shank 8 may taper slightly toward the end thereof.

The extension C preferably comprises an intermediate portion 10 and has the one 85 end thereof of tubular formation and providing a socket 11 for the reception of the shank 8. The tapered shank 8 may be forced into the socket 11 until the shoulder 9 abuts the end of the socket, and will be 90 frictionally engaged by the inner walls of the socket 11. If desired, a rivet 11^a may be passed thru the socket 11 and shank 8 to further secure the extension C to the stem B. The intermediate portion 10 of the extension C is preferably of smaller diameter 95 than the socket 11 so as to reduce the weight thereof in addition to providing an increased area on the scraper D for the reception of particles scraped from a hole. A reduced 100 end 12, preferably square in cross section, is formed on the intermediate portion 10 opposite to the socket end 11, defining a shoulder 13.

The scraper D herein shown as a disc, provided with an aperture 14 of a cross section corresponding to the square end 12, is fitted on the reduced end 12 until the face 15 abuts the shoulder 13 and may be removably secured thereon by means of a suitable 110 detachable securing device, such as a nut 16 threaded onto the end 12. It is obvious

that this scraper D may be made of various shapes and sizes to accommodate different purposes.

Referring now to the tamping head E, it 5 preferably is formed integral with the stem B at the end opposite to the shank 8. This head E preferably is of a diameter greater than the stem B and is provided with a longitudinal groove 18 extending therethrough, 10 the purpose of which will appear hereinafter. The cap F is carried by the head E at the outer end thereof and is detachably secured thereto by suitable devices, such as screws 19. This cap F is also provided with 15 a groove 20 which is aligned with the groove 18 in the head E. The purpose of this cap F is to prevent the head E from wearing or splitting.

In practice, as a hole is being drilled for 20 the admission of an explosive charge, the scraper or tamping rod A is frequently inserted into the hole, the scraper D being innermost and particles that have become detached by drilling are scraped on to the 25 face 15 of the scraper D and are removed from the hole. When a hole has been drilled to a desired depth and all of the particles removed therefrom, an explosive charge is 30 inserted into the hole with the usual fuse or electric wire leads connected thereto and leading exteriorly of the hole, said fuse or 35 wires being adapted to ignite the explosive charge in due course of the operation, tamping material is introduced into the hole and packed against the explosive charge by 40 reversing the rod A, and pounding with the head E and cap F. During this part of the 45 operation the grooves 18 and 20 serve to protect the fuse or wires which extend into the hole from some exterior point, and upon reciprocation of the head E will slide freely in the grooves 18 and 20.

If desired all of the metal parts, such as 45 the extension C, scraper D, nut 16, and cap F may be made of copper so as to obviate the possibility of causing a spark by coming in contact with a flinty substance when being used in a hole, thus avoiding premature and inopportune explosions should such a 50 spark contact with inflammable gas, coal dust or anything ignitable.

Changes in details may be made to the form of invention herein shown and described without departing from the spirit of the invention or scope of the claims. 55

I claim:

1. A device of the class described comprising a stem, a tamping head formed on one end of said stem, a cap removably secured to said head, an extension carried by 60 said stem at the end opposite to said head, and a scraper removably secured to said extension.

2. A device of the class described comprising a stem, an enlarged head formed in one end of said stem, said head provided with a longitudinal groove, a cap removably secured to said head, said cap provided with a groove aligning with said groove in said head, an extension carried by said stem at 65 the end opposite to said head, and a scraper removably secured to said extension. 70

3. A blasting tool comprising an elongated stem portion, a relatively shorter metal extension connected to an end of said stem and of heavier material than said stem, and a scraper removably carried at an 75 end of said metal extension.

4. A blasting tool comprising a relatively long wooden stem providing a tamping head 80 at one end thereof, a relatively short metal extension connected at the opposite end of said stem, and a scraper carried at the free end of said extension.

5. A blasting tool comprising an elongated wooden stem of relatively light weight having at one end thereof a laterally enlarged tamping head of cylindrical formation providing a groove longitudinally thereof, a wear cap on the outer face of said tamping head having a groove therein aligning with the groove of said tamping head, said stem at its opposite end providing a reduced shank, a metal extension relatively short in comparison to the length of 95 said stem providing a socket adapted to receive the reduced shank of said stem and outwardly of said socket providing a reduced portion, a scraper, and means for detachably connecting the scraper at the free end of the reduced portion of said extension. 100

JOHN JAMES DIXON.
